(57) **CLAIM**

The ornamental design for a gate-flap portfolio, as shown and described.

DESCRIPTION

FIG. 1 is a front view of a first embodiment of a gate-flap portfolio in a closed position showing my new design;

FIG. 2 is a front view of the gate-flap portfolio of FIG. 1 in an open position, displaying upper and lower internal pockets; FIG. 3 is a rear view of the gate-flap portfolio thereof;

FIG. 4 is a front, top perspective view of the gate-flap portfolio of FIG. 1 in a partially open position;

FIG. 5 is a front view of a second embodiment of a gate-flap portfolio in a closed position showing my new design;

FIG. 6 is a front view of the gate-flap portfolio of FIG. 5 in an open position, displaying upper and lower internal pockets; FIG. 7 is a rear view of the gate-flap portfolio thereof; and,

FIG. 8 is a front, top perspective view of the gate-flap portfolio of FIG. 5 in a partially open position.

The card holding slots shown in broken lines in FIGS. 2, 4, 6, and 8 represent portions of the portfolio that form no part of the claimed design.
